UNITED STATES PATENT OFFICE.

FRANK L. SESSIONS, OF COLUMBUS, OHIO, ASSIGNEE TO THE JEFFREY MANUFACTURING COMPANY, A CORPORATION OF OHIO.

GRID-RESISTANCE.

1,031,382.

Specification of Letters Patent. Patented July 2, 1912.

Application filed October 21, 1909. Serial No. 523,863.

To all whom it may concern:

Be it known that I, FRANK L. SESSIONS, a citizen of the United States, residing at Columbus, in the county of Franklin and State of Ohio, have invented certain new and useful Improvements in Grid-Resistances, of which the following is a specification, reference being had therein to the accompanying drawings.

10 This invention relates to improvements in resistances of the grid type.

The object of the invention is to provide satisfactory means for electrically connecting together the ends of the grids and for satisfactorily connecting the lead wires to the grids.

In the accompanying drawings, I have shown one embodiment of my invention. I do not desire, however, to be limited to the exact form of construction which I have shown, and various changes of detail may be made within the scope of my invention.

Of the drawings—Figure 1 is a side elevation of a grid resistance embodying my invention, a portion being shown in cross section. Fig. 2 is a plan view. Fig. 3 is a detail view of one of the grids. Figs. 4 and 5 are detailed views of one of the wire connectors. Figs. 6 and 7 are detail views of one of the connecting washers. Fig. 8 is a detail view of one of the connecting staples.

Referring to the drawings, 1 represents a grid. So far as my present invention is concerned, this grid may be of any usual or desired form. That which I prefer, however, and which I have shown in the drawings for purposes of illustration, is zig-zag in shape to form a resistance element having as long a path as possible for the current.

The grid is provided with supporting rings, preferably three in number, and cast integral with the resistance element. These rings are designated in the drawings by 2.

45 At each end of each grid is formed a projection 3 having thereon one or more, preferably two, small holes 4. These holes should preferably be drilled and reamed so that they will be slightly tapering.

50 The resistance as a whole is built up of a plurality of the grids above described. One convenient means of supporting the grids is shown in the drawings.

55 5, 5 are end frame plates and are provided with lugs 6, 6, by means of which the

resistances may be bolted to the frame of the locomotive or to any other device in connection with which it is to be used. Each of the plates 5 is provided with apertures to correspond with the holes in the rings 2. 60 The bolts 7, 7 are each provided with an insulating tube 8 and are passed through the openings in the plates and grids. By means of the nuts on the bolts 7, the plates and grids are securely locked together. Insulating washers 9 and 10 are provided to prevent electrical communication between the grids and the plates. Between the middle rings of the various grids I provide insulating washers 11. Between the end rings 70 of the grids I provide either washers of conducting material, such as copper, or washers 12 of insulating material, according to whether or not I desire to form electrical connection between the ends. The copper 75 washers may be of either of two forms designated in the drawings by 13 and 14 respectively. Those marked 13 are simply flat sheet washers. The washers 14 are best shown in Figs. 6 and 7. It will be noted 80 that they comprise simply a sheet of metal doubled upon itself to form two parallel connected washers. The double washers 14 are of such size that one or two or even more grids may be inclosed between the two parallel parts thereof. In the drawings, I have shown them inclosing two grids.

15 is a staple, preferably formed of copper wire and adapted to enter the tapered holes 4 in the ends of the grids. These 90 staples may be used for connecting together the ends of the grids in any one of a large variety of ways.

16, 16^a, and 17 represent connectors for the lead wires. The connector 17 is adapted 95 to receive two wires, while the connectors 16 and 16^a are adapted to receive but one each. Otherwise their construction is identical, and will be best understood by a reference to Figs. 4 and 5. The wire engaging part may 100 be of any well known construction and is provided with a wire receiving aperture and set screws to hold the wire in place.

17^a is an attached washer and is adapted to be inserted between two grids to take the 105 place of one of the washers 13 or 14.

18 is an aperture similar to the apertures 4 in the grids. This makes it possible for the connector to be directly bonded to one of the grids.

In Fig. 1, I have shown the grids connected in series between the connectors 16 and 16^a. Between the connectors 16^a and 17 the grids are connected in a double parallel series. This arrangement is shown merely for purposes of illustration, and by interchanging the staples, the various washers and the lead wire connectors, an almost infinite variety of resistances can be obtained.

10 It will be noted that I have obtained by my invention a very direct and certain electrical connection between the grids. For instance, in the upper left hand corner of Fig. 1 where the four ends are connected together, it will be noted that all four are connected in three distinct ways, first directly through one another; second through one another by means of the staples 15; third through the connecting part of the double 15 washer 14.

15 In the drawings, I have shown the staples 15 as of sufficient length to extend the greater part of the distance through the apertures 4. It may, however, be found preferable in some cases to make the staples shorter and to provide two series of staples, one series for the ends of the apertures 4, which are on one side of the resistance, and the other series for the opposite ends of the 20 apertures 4.

25 What I claim is—

30 1. In a grid resistance, the combination of a plurality of grids, insulated means for supporting said grids in parallel relation to one another, and a double washer of conducting material comprising two parallel parts with a connector between, each of said parallel parts of the washer being adapted to lie between and in engagement with two grids, 35 substantially as set forth.

40 2. In a grid resistance, the combination of a plurality of grids, insulated means for supporting said grids, and a connecting member of conducting material comprising a plurality of connected parts, each of said parts

being adapted to lie between and engage with two grids, substantially as set forth.

45 3. In a grid resistance, a plurality of grids arranged in parallel relation one with another, each grid being provided at each end with an aperture, the apertures in the corresponding ends of all of the grids being parallel to one another and similarly located, and a plurality of staples consisting of a wire bent with one part parallel to another part, the said parts being adapted to enter the apertures of two grids, substantially as set forth.

50 4. In a grid resistance, the combination of a plurality of grids, insulated means for supporting said grids, and a lead-wire connector having a part adapted to engage with one end of one of the grids, said grid and said connector being each provided with small elongated apertures, which apertures are 55 parallel to one another, and a staple consisting of a wire bent with one part parallel to another part, the said parts being adapted to enter the apertures of the grid and the connector, substantially as set forth.

55 5. In a grid resistance, the combination of a plurality of grids, insulated means for supporting said grids in parallel relation to one another, a double washer comprising two parallel washer-like plates with a connector 60 between, each of the said washer-like plates lying between and in engagement with two grids, each of the grids with which the double washer engages having a small elongated aperture and a plurality of connecting staples adapted to enter the said apertures and 65 electrically connect the said grids, substantially as set forth.

70 In testimony whereof I affix my signature, in presence of two witnesses.

FRANK L. SESSIONS.
